UNITED STATES PATENT OFFICE.

PETER FOLTYN, OF NEW YORK, N. Y.

STOVE.

Application filed November 30, 1925. Serial No. 72,186.

This invention relates to heaters for rooms, compartments, tents, and the like, the object being to construct a heater to burn sawdust, shavings, and other waste combustible matter, which requires no attention after a fire is started, and which is simple in construction and operation and decidedly inexpensive, safe and sanitary.

A feature of my present invention resides in a double cylinder drum shell construction providing a circular smoke chamber to receive the products of combustion and convey them to a suitable outlet to be connected to a flue or chimney.

15 A further feature of the invention resides in the provision of core bodies which are arranged before the sawdust is introduced into the inner or combustion cylinder to form draft channels or passages for the free circulation of the air through the sawdust to enhance the operation of the heater and incite combustion.

I have illustrated a preferred embodiment of my invention in the accompanying drawings in which:—

25 Fig. 1 is a central sectional elevation of my improved heater showing the core bodies in position to form air channels after the sawdust has been tamped and said cores removed.

30 Fig. 2 is a partial section of the heater with the cores removed and the sawdust charge ready for igniting.

Fig. 3 is a horizontal section on the line 3—3 of Fig. 2.

35 Fig. 4 is a fragmentary vertical cross section on the line 4—4 of Fig. 2.

Fig. 5 is a detail perspective showing a 40 channeled molded sawdust block which may be used as fuel for my heater.

Referring to the drawings, 10 and 11 are the outer and inner spaced cylinders or drums forming the body of my improved heater, the latter being removable, and providing a circumferential space or smoke chamber 12 to receive and direct the products of combustion to the flue or chimney 13.

45 The outer cylinder or drum 10 is formed with a bottom 14, shaped to provide a cross sectional semi-circular trough 15, and the inner cylinder or drum 11 is formed with an outwardly directed short cross sectional semi-circular extension 16 to register with 50 the outer end portion of trough 15, and to

gether form a short air tube 17 across the smoke chamber 12. This tube is normally open but may be partially closed when the heater is operating to regulate the inflow of air by a damper or valve plate 18, slideable 60 in guides 19, which frictionally hold the valve plate on any elevation.

The heater may be closed at the top when in operation by a cover 20 resting on the outer cylinder or drum 10, somewhat above the 65 upper end of the inner cylinder or shell 11 to provide free passage for the said products of combustion on their way to the flue or chimney.

70 The heater may be provided with feet or rests 21 to space it from the floor.

To properly place the removable inner cylinder 11 so that the sections of the air tube 17 register when the parts are assembled, I provide the said inner cylinder with radial lugs 22, one or more engaging sockets 23 on the bottom 14 of the outer one, to prevent a relative turning movement of the cylinders.

75 In Fig. 5 of the drawing, I have shown a cast or molded sawdust disk or block 25 having air channels or passages 26 and disks of this character may be used as fuel in my heater in lieu of loose sawdust. The disks may be prepared by using the waste 80 liquor of paper pulp manufacture (sulphite liquor) starch etc., as a binder for the sawdust.

85 When recharging the heater prior to starting a new fire, I pass a core 27 through the air tube 17 and into and along the trough 15 to about the center of the cylinder 11, after which I place another vertically and centrally arranged core 28 in the said cylinder. The sawdust is then introduced and packed or tamped around the core 28 until the combustion chamber 29 is filled, after which the cores are removed, leaving air channels 30 and 31, and a match or torch is then applied to the charge 100 through air tube 17 after the cover 20 is placed in position.

90 The inner cylinder 11 may be made with a separate bottom, so that after combustion said cylinder may be lifted out of the outside cylinder 10 and the possible ashes removed. In this case air shaft 17 is placed entirely above the bottom of cylinder 11.

105 What I claim as new, is:—

110 1. A heater comprising spaced cylinders,

one having a bottom formed with a cross-sectional, semi-circular trough, the other being open ended and provided with a cross-sectional semi-circular extension adapted to register with the trough and together form an air inlet tube spanning the space between said cylinders, thereby forming an air passage to the firing charge.

2. In a heater, an outer cylinder provided with a bottom having a cross-sectional, semi-circular trough, an inner cylinder having spacing lugs and a cross-sectional, semi-circular extension to register with said trough to form an air tube spanning the space between said cylinders thereby forming an air passage to the firing charge, said outer cylinder having sockets to receive said

spacing lugs to lock the parts against relative movement.

3. In a heater, an outer drum having a removable cover, an outlet flue and a bottom formed with a cross-sectional semi-circular trough, an inner drum having semi-circular extension registering with said trough to collectively form an air inlet tube spanning the space between the drums thereby forming an air passage to the firing charge, and a valve to control the passage of air into said tube, as described.

Signed at New York city in the county and State of New York this 18th day of November A. D. 1925.

PETER FOLTYN.
